[57] CLAIM

The ornamental design for a rub rail for an automobile, as shown and described.

DESCRIPTION

FIG. 1 is a perspective view of a rub rail for an automobile showing our new design, taken from the top, front and one end thereof;

FIG. 2 is an end elevation view thereof;

FIG. 3 is an opposite end elevation view thereof;

FIG. 4 is a front elevation view thereof;

FIG. 5 is a top plan view thereof;

FIG. 6 is a bottom plan view thereof; and

FIG. 7 is a rear elevation view thereof.

The rub rail has been broken away in the middle of FIGS. 1, 4, 5, 6 and 7 to indicate indeterminate length.
